UNITED STATES PATENT OFFICE.

JAMES BORDEN CLARK, OF MORGAN CITY, LOUISIANA.

POLE-CLIMBER.

1,147,609.

Specification of Letters Patent. Patented July 20, 1915.

Application filed May 17, 1915. Serial No. 28,678.

To all whom it may concern:

Be it known that I, JAMES BORDEN CLARK, a citizen of the United States, residing at Morgan City, in the parish of St. Mary and State of Louisiana, have invented certain new and useful Improvements in Pole-Climbers; and I do declare the following to be a full, clear, and exact description of the invention, such as will enable others skilled in the art to which it appertains to make and use the same.

My invention relates to improvements in linemen's equipment and more particularly to pole climbers, the object of the invention being to improve upon the general construction of such devices now on the market, to such an extent as to prevent the shanks thereof from turning when in operation and chafing the legs of the user.

With this general object in view, the invention resides in certain novel features of construction hereinafter fully described and claimed, two embodiments of the invention being illustrated in the accompanying drawings which constitute a part of the application and in which,

Figure 1 is a side elevation of a climber constructed in accordance with the invention; Fig. 2 is a horizontal sectional view as seen along the plane indicated by the line 2—2 of Fig. 1; Fig. 3 is a vertical transverse section as viewed along the plane of the line 3—3 of Fig. 1; and Fig. 4 is a detail side elevation of the upper end of a climber showing a slightly different form of construction.

In describing the invention, I shall refer first to that form disclosed in Figs. 1 to 3 of the drawings by referring to such figures by similar reference characters placed on corresponding parts. To this end, 1 indicate the upright shank of the climber having the usual prong 2 and foot stirrup 3 at its lower end, while its upper end is equipped with the commonly used strap receiving loop 4.

Secured by rivets or the like 5 to the upper end of the shank 1 and in contact with the inner side thereof, is the substantially oval arcuate leg engaging plate 6 whose edges are preferably curved outwardly at 7, whereby to prevent injury to the clothing or limbs of a person using the device. The plate 6 is of such design as to substantially conform to the shape of the inner side of the user's leg with which it contacts, but it is essential (see Fig. 2) that said plate extend forwardly to such an

extent as to position its front end in advance of the user's shin. This front end carries one or more hinge knuckles 8 which align with similar construction 9 on the front end of an additional and smaller arcuate leg 60 engaging plate 10 which is adapted to contact with the muscles on the outer side of the leg when applied to use, a rivet or the like 11 being passed through the aligned knuckles 65 whereby to hingedly connect the same, thus allowing the plate 10 to be swung forwardly to inactive position, when the strap 12 is released. This strap 12 is received not only by the loop 4, but by additional loops 13 70 which are punched outwardly from the plate 6, and by an additional loop 14 formed in a similar manner upon the horizontally swinging plate 10, whereby said strap will be at all times correctly positioned for application to use for the purpose of anchoring the upper end of the shank 1, the lower end of the latter being provided with the usual strap 15.

In Fig. 4, the construction illustrated is 80 identical with that previously described, with the exception that the leg engaging plate 6^a is formed as an integral part of the shank 1, this construction being equally as simple and efficient as that derived by forming the shank and the plate in two separate parts and securing the same together. Regardless of the exact details of construction employed, however, it will be evident that the arcuate plate carried by the upper end 85 of the shank and engaging the lineman's leg when applied to use, will prevent said shank from turning or producing the undesirable effects caused by such shanks when provided with no pads or the like at their upper 90 ends. If desired, the numerous plates may be padded with wool, leather, etc., but since this detail of construction is optional with the user, it is not deemed necessary to illustrate the same.

I claim:

1. The combination with a climber comprising an upright shank having prong means and a foot stirrup at its lower end, of an upright arcuate leg engaging plate 105 carried by the upper end of the shank, an additional and horizontally swinging leg engaging plate hinged to one end of the aforesaid plate, and a leg embracing strap carried by the two plates.

2. The combination with a climber comprising an upright shank having prong

means and a foot stirrup at its lower end, of an upright arcuate leg engaging plate carried by the upper end of the shank, an additional arcuate and horizontally swinging leg engaging plate hinged to one end of the aforesaid plate, strap receiving loops on the two plates, and a leg embracing strap passed through said loops.

In testimony whereof I have hereunto set my hand in presence of two subscribing witnesses. 10

JAMES BORDEN CLARK.
